UNITED STATES PATENT OFFICE.

CHARLES ALGERNON PARSONS, OF NEWCASTLE-UPON-TYNE, AND ROBERT JOHN WALKER, STANLEY SMITH COOK, AND LOUIS MORTIMER DOUGLAS, OF WALLSEND, ENGLAND; SAID WALKER, SAID COOK, AND SAID DOUGLAS ASSIGNEES TO SAID PARSONS.

TURBINE INSTALLATIONS FOR SHIP PROPULSION.

1,281,824.

Specification of Letters Patent. Patented Oct. 15, 1918.

Application filed May 31, 1918. Serial No. 100,892.

To all whom it may concern:

Be it known that we, The Honorable Sir CHARLES ALGERNON PARSONS, K. C. B., of Heaton Works, Newcastle-upon-Tyne, in the county of Northumberland, England, ROBERT JOHN WALKER, STANLEY SMITH COOK, and LOUIS MORTIMER DOUGLAS, all of Turbinia Works, Wallsend-upon-Tyne, in the county of Northumberland, England, all subjects of the King of Great Britain and Ireland, have invented certain new and useful Improvements in and Relating to Turbine Installations for Ship Propulsion, of which the following is a specification.

15 The present invention relates to turbine installations for ship propulsion of the type in which the ratio of the revolutions of a main turbine to the revolutions of the propeller it drives differs at low powers from 20 the ratio at full power.

Such installations are disclosed, for example, in United States specification Serial No. 51,493.

In all the arrangements disclosed in the above application, in which full power gearing is provided, the full power gearing is rendered inoperative when the low power gearing is in operation, and vice versa.

The object of the present invention is to 30 provide installations of the type indicated, in which at low and intermediate powers some or all of the full power gearing forms part of the train by which different-revolution ratios are obtained, in such a manner 35 that the final member of the train can be located co-axially with and rotates in the same direction as the propeller shaft.

The invention consists in the improved ship propulsion installations hereinafter 40 described.

Referring to the accompanying diagrammatic drawings:—

Figure 1 is a plan of an engine room, showing a single shaft installation embodying one form of the present invention.

Fig. 2 illustrates a modification in which a cruising turbine is employed.

Fig. 3 illustrates a modification similar to the form of the invention shown in Fig. 1, but in which both the high and low pressure turbines operate at all times through gearing.

Fig. 4 illustrates a third modification in

which high, intermediate and low pressure turbines are provided.

55

Figs. 5 and 6 illustrate a fourth modification, in which four speed ratios are available.

Fig. 7 illustrates a fifth modification.

Fig. 7^a is a detail view of the clutch shown in Fig. 7.

Fig. 8 illustrates a sixth modification.

Fig. 9 illustrates an alternative construction similar to that shown in Fig. 8, but in which high, intermediate and low pressure turbines are provided.

Fig. 10 illustrates a seventh modification, in which a two-shaft installation is provided on one shaft with turbines and gearing similar to that described with reference to Fig. 2, while the other shaft is provided with a high pressure, low pressure and cruising turbine, the high pressure and cruising turbines operating the propeller shaft through gearing, and the low pressure turbine directly.

70

Fig. 11 illustrates an eighth modification, showing a similar installation to that illustrated in Fig. 10, except that the low pressure turbines on both shafts operate through gearing.

Fig. 12 illustrates a ninth modification, in which an installation similar to that illustrated in Figs. 5 and 6 is employed, except that the additional shaft carrying gearing is connected through a suitable clutch to a cruising turbine, by which means four speed ratios are available, and means are provided for obtaining an efficient range of expansion at all powers.

90

In carrying the present invention into effect according to one form, and as shown in Fig. 1, and as applied to the case of a single propeller shaft installation, a high pressure turbine *a* and a low pressure turbine *b* are provided. The low pressure turbine is mounted co-axially with the propeller shaft *c* which latter constitutes a final driven member. The high pressure turbine is situated adjacent to the low pressure turbine with its axis parallel to the propeller shaft. Upon the propeller shaft and adjacent to the low pressure turbine two gear wheels of unequal size are provided. For convenience, one of these, *d*, namely, that nearer to the low pressure turbine, will be

95

100

105

called the full power gear wheel, while the other, *e*, will be called the low power gear wheel. The full power gear wheel may be permanently connected to the low pressure 5 turbine rotor *j*.

Upon the shaft *l* of the high pressure turbine, or upon an extension of this shaft, two gear pinions *f* and *g* are mounted, one in engagement with the full power gear wheel; 10 the other in engagement with the low power gear wheel.

A clutch *h* is provided between the two gear wheels such that the low power wheel *e* may be connected to or disconnected from the propeller shaft, while the low pressure turbine rotor *j* may be connected to or disconnected from the propeller shaft.

A clutch *k* is provided between the two pinions on the high pressure turbine shaft 20 so arranged that the low power pinion *g* can be connected to or disconnected from the shaft *l* of the high pressure turbine. The pinion *f* engaging the full power gear wheel *d* may be permanently coupled to the shaft 25 of the high pressure turbine.

Under full power conditions the low pressure turbine rotor *j* is connected to the propeller shaft and the low power gear wheel *e* is disconnected from the propeller shaft, 30 and the low power pinion *g* is preferably disconnected from the high pressure turbine shaft.

Steam is admitted to the high pressure turbine by the conduit 1, from whence it 35 passes by the conduit 2 to the low pressure turbine, and then to the condenser.

Under these conditions the low pressure turbine *b* drives the propeller shaft *c* directly, while the high pressure turbine *a* 40 drives the propeller shaft through single reduction or primary gearing provided by the full power pinion *f* and gear wheel *d*.

Under low power conditions the low power gear wheel *e* is connected to the propeller shaft, and the low pressure turbine 45 rotor *j* is disconnected from the propeller shaft, while the low power pinion *g* is connected to the shaft *l* of the high pressure turbine.

Steam is admitted to the high pressure turbine and passes to the low pressure turbine and thence to the condenser.

The high pressure turbine *a* drives the propeller shaft through the low power pinion *g* and gear wheel *e*, said pinions *g* and *e* 55 constituting secondary gearing, while the low pressure turbine *b* drives the propeller shaft through the full power or primary and low power or secondary gearing *d*, *f*, and *g*, *e*, in series.

Owing to the difference in diameter of the two gear wheels *d* and *e* upon the propeller shaft and the two pinions *f* and *g* engaging with them, the high and low pressure turbines thus at low power drive the propeller.

shaft through a transmission giving a different ratio to that employed at full power. Further, it is to be noted that under low power conditions the low pressure turbine drives through two gear pairs in series, while at full power it drives directly.

According to an alternative arrangement, a cruising stage is fitted to the high pressure turbine *a*.

In a modified construction (see Fig. 2) the same parts are provided as in the first described form (Fig. 1) with the addition of a cruising turbine *m* arranged with its pinion *n* in engagement with the full power pinion *f* of the high pressure turbine. The clutches *h* and *k* already described are provided in this modification, and an additional clutch *o* may be provided between the high pressure turbine and its full power pinion *f*, while a clutch *p* is provided between the cruising 85 turbine and its pinion *n*.

Under full power conditions the cruising turbine is disconnected and the installation operates as in the first described form.

Under low power conditions, the cruising 90 turbine is connected to its pinion *n*, and the high pressure turbine disconnected from the pinion by the clutch *o*.

Steam is admitted to the cruising turbine by the conduit 3, from whence it passes by 95 the conduit 4 to the low pressure turbine. In this modification the high pressure turbine *a* remains stationary under low power conditions.

According to a second modification (see 100 Fig. 3), instead of the low pressure turbine *b* being mounted coaxially with the propeller shaft it may be located to one side of the propeller shaft and geared to the full power gear wheel *d* through a suitable pinion *g*. In this modification at full powers both the high and low pressure turbines operate the propeller shaft through single reduction gearing *f*, *d*, and *g*, *d*, while at low powers the high pressure turbine *a* operates 110 through single reduction gearing *g*, *e*, giving a different ratio to that obtaining at high powers, while the low pressure turbine *b* operates through three gear pairs *g*, *d*, *d*, *f*; and *g*, *e* in series.

According to a third modification (see 115 Fig. 4) two gear wheels *d* and *e* are provided upon the propeller shaft *c* as in the second modification (Fig. 3).

High pressure *a*, intermediate pressure *r* 120 and low pressure turbines *b* are provided having pinions *f*, *t*, *q*, *g*, engaging the full power gear wheel *d*. The shaft of the low pressure turbine is extended and carries a pinion *q'* which engages the low power gear 125 wheel *e* and corresponds to the pinion *g* in Fig. 3, a suitable clutch *h'* being provided between the two pinions *g* and *q'* which are coaxial with the low pressure turbine.

According to a fourth modification (see 130

Figs. 5 and 6) in which four speed ratios are available, two gear wheels d , e , are provided upon the propeller shaft c , as in the second modification (Fig. 3).

The spindles of the high pressure and low pressure turbines a and b are both extended and each carries two pinions f and g engaging the full power gear wheel d , and g and g' the low power gear wheel e . Clutches h and h' are provided on each of the turbine shafts between the pinions on those shafts. A further additional shaft s is provided carrying a wheel u and pinion v , the wheel u engaging with the full power gear wheel and the pinion v engaging with the low power gear wheel. A clutch w is provided on this shaft between the wheel and pinion. Under full power conditions the full power gear wheel d is clutched by h to the propeller shaft c while all the remaining clutches are opened. Under these conditions the high pressure and low pressure turbines drive the propeller shaft through single reduction gearing f , d ; g , d ; as in the second modification.

Under the lowest power conditions the full power gear wheel d is disconnected from the shaft c , and the low power gear wheel e connected to the propeller shaft c . The clutch h between the pinions on the high pressure turbine shaft is closed while the clutch h' between the pinions on the low pressure turbine shaft is operated to disconnect g' from the shaft of b and the clutch w on the additional shaft is opened. Under these conditions the power of a and b is transmitted to the low power gear wheel e through the pinion g on the high pressure turbine shaft.

Under the lower intermediate power conditions the full power gear wheel d is disconnected from the propeller shaft c , and the low power gear wheel e connected to the propeller shaft. The clutches h and h' between the pinions on the shafts of the turbines are opened while the clutch w between the wheel and pinion on the additional shaft s is closed. Under these conditions the high and low pressure turbines drive on to the full power gear wheel d from which the drive is transmitted to the low power gear wheel e through the wheel u and pinion v upon the additional shaft s .

Under the higher intermediate power conditions the clutch w upon the additional shaft is opened and the clutch h between the pinions on the high pressure turbine shaft is opened, while the clutch h' between the pinions on the low pressure turbine shaft is closed. Under these conditions the power of a and b is transmitted to the propeller shaft through the low power gear wheel e and the pinion g' on the low pressure turbine shaft.

It will be understood that the full power

gear wheel d upon the propeller shaft operates at low power conditions as an idle wheel.

According to a fifth modification (see Fig. 7) high and low pressure turbines a and b and a gear wheel d' are provided, the gear wheel being mounted on a shaft c' coaxial with the propeller shaft c . Rotatably mounted upon the gear wheel shaft c' is a pinion x . Adjacent to this pinion a second gear wheel e' is freely mounted upon the propeller shaft c .

An additional shaft s' lying parallel with the propeller shaft carries a wheel and a pinion, the wheel u' engaging with the pinion x upon the gear wheel shaft and the pinion v' with the second mentioned wheel e' upon the propeller shaft.

Suitable clutch means h' and h'' are provided between the pinion x on the gear wheel shaft and the second mentioned wheel e' upon the propeller shaft.

Under full power conditions the gear wheel shaft c' is clutched to the propeller shaft c by drawing the parts h' and h'' into engagement (see Fig. 7a). Consequently the high and low pressure turbines drive the propeller shaft c through single reduction gearing formed of the pinions f and g upon their spindles, and the first mentioned gear wheel d' .

Under low power conditions the gear wheel shaft c' is disconnected from the shaft c by separating the parts h' and h'' , the second mentioned gear wheel e' upon the propeller shaft is clutched to that shaft by the part h'' and the gear wheel x to the shaft c' by the part h' (see Fig. 7). Under these conditions the turbines drive through two sets of gearing in series, namely, through the pinions f and g on their shafts to the first mentioned gear wheel d' , thence from the pinion x on the gear wheel shaft c' to the gear wheel u' upon the additional shaft s' and from the pinion v' on the additional shaft back to the second mentioned gear wheel e' upon the propeller shaft c .

It will be seen that the arrangement is such that the direction of rotation of the propeller shaft c remains the same under both power conditions and the gears e' , v' , u' and x are at rest at full power.

According to a sixth modification (see Fig. 8) two gear wheels d and e are provided upon the propeller shaft c with clutch means whereby either can be connected to the shaft.

High and low pressure turbines a and b are provided gearing with one of the gear wheels, namely, the full power gear wheel d , through suitable pinions f and g . An additional shaft s carrying a gear wheel and pinion with a clutch w between them is mounted parallel with the propeller shaft.

A gear wheel u upon this shaft engages the

full power gear wheel d while the pinion v engages the low power gear wheel e upon the propeller shaft.

Under full power conditions the full power gear wheel d is connected with the propeller shaft c and the low power gear wheel e disconnected, and the clutch w upon the additional shaft is opened. The turbines thus drive the propeller shaft c through single reduction gearing, $f, d; g, d$.

Under low power conditions the full power gear wheel d is disconnected from, and the low power gear wheel e clutched to, the propeller shaft c , and the clutch w upon the additional shaft is closed. Under these conditions the turbines drive the propeller shaft c through two gear trains in series, namely, through their pinions f and g to the full power gear wheel d from which the drive is taken through the additional shaft s to the low power gear wheel e mounted upon the propeller shaft.

According to an alternative construction (see Fig. 9) the place of the high pressure turbine a in the last modification (Fig. 8) may be taken by an intermediate pressure turbine r , while the high pressure turbine engages with the gear wheel upon the additional shaft through a suitable pinion f on its spindle.

According to a seventh modification (see Fig. 10) as applied to a two-shaft installation, one of the shafts c is furnished with turbines a and b , gearing d, e, f, g , and clutches h, h , as in the first described form (Fig. 1) while the other shaft c^2 is provided with a low pressure turbine b^2 coaxial with the propeller shaft c^2 , and a high pressure turbine a^2 alongside the propeller shaft and connected thereto through a single reduction gearing d^2, f^2 . A clutch h^2 is provided between the low pressure turbine b^2 and the propeller shaft c^2 and a clutch h^2 between the high pressure turbine a^2 and its pinion f^2 . Upon the shaft of the pinion f^2 of the high pressure turbine a^2 a gear wheel y is provided with which the pinion n of a cruising turbine m engages. A clutch o^2 is provided between the last mentioned gear wheel y and the high pressure turbine pinion f^2 .

Under full power conditions the cruising turbine gearing n, y , is disconnected, the high pressure turbines a and a^2 connected to their pinions f and f^2 , and the low pressure turbines b, b^2 , directly connected to their propeller shafts. The low power gear wheel e upon the first mentioned propeller shaft c is disconnected and the low power pinion g is disconnected from the high pressure turbine a . Steam is admitted by the conduit 1 to both high pressure turbines which exhaust by conduit 2 to their low pressure turbines. The propeller shafts are then driven directly by the low pressure turbines and by the high pressure turbines operating through single reduction gearing.

Under cruising conditions the cruising turbine is connected to the second mentioned propeller shaft and the high and low pressure turbines of that shaft disconnected.

The low power gearing e, g , of the first mentioned propeller shaft is connected up and live steam admitted by the conduit 3 to the cruising turbine. The exhaust from the cruising turbine passes by conduit 4 to the low pressure turbine b upon the first mentioned propeller shaft.

Auxiliary exhaust steam is led by conduit 5 to the high pressure turbine a on the first mentioned propeller shaft c , and exhausts to the low pressure turbine b upon the same shaft.

Under these conditions one of the shafts c^2 is driven by the cruising turbine m operating through double reduction gearing, and the other shaft c is driven by its main turbines operating through supplementary gearing giving a different ratio from that obtaining under full power conditions.

The steam flow employed in this modification at low powers is similar to that disclosed in United States specification Serial No. 51496.

In cases where auxiliary exhaust steam is not employed in the last described modification, the high pressure turbine a may be disconnected from its pinion g by a clutch o .

As an alternative, the cruising turbine m may operate through single reduction gearing.

As a further alternative the cruising turbine m may exhaust to the high pressure turbine a instead of the low pressure turbine b on the propeller shaft c .

As a further alternative, the cruising turbine m may exhaust to the high pressure turbine a^2 upon its own propeller shaft c^2 , from which the exhaust passes to the low pressure turbine b on the other shaft c .

According to an eighth modification (see Fig. 11) as applied to a two-shaft installation, one of the shafts c is provided with turbines, gear wheels and clutches similar to those provided on the second mentioned propeller shaft c^2 of the last described modification, except that the low pressure turbine b^2 is not coupled directly to the shaft c^2 , but gears with the wheel d^2 by the pinion g^2 . The other propeller shaft c is provided with turbines, gearing and clutches similar to those described with reference to the second modification already described with reference to Fig. 3.

In this eighth modification under cruising conditions steam is admitted to the cruising turbine m from whence it is exhausted to the high pressure turbine a upon the other shaft by the conduit 4.

According to a ninth modification (see

Fig. 12) as applied to a single shaft installation, high and low pressure turbines and gearing similar to that described with reference to Figs. 5 and 6 is provided. The shaft *s* in this modification, however, is connected through a suitable clutch *p* with the cruising turbine *m*, and the cruising turbine and the high pressure turbines are provided with two inlet conduits, so arranged that the range of expansion in the turbines may be varied to meet the requirements of the various power outputs. At the lowest powers when the propeller shaft *c* is revolving at its lowest speed, the largest reduction ratio is employed by closing the clutches *w* and *p*, and opening the clutches *k'* and *k*, while the clutch *h* is operated to connect the low power gear wheel *e* to the propeller shaft *c*. The range of expansion in the turbines is maintained by admitting steam to the first stage of the cruising turbine *m* by the connection 3.

At the next higher power the larger quantity of steam required is passed by admitting live steam to a later stage of the cruising turbine by the conduit 7, and the required smaller reduction ratio suitable for this power is obtained by closing the clutches *p* and *k*, opening the clutches *k'* and *w* and keeping the clutch *h* in the same position as at the lowest power.

At the next higher power the still larger quantity of steam required is passed by admitting live steam to the first stage of the high pressure turbine by the conduit 8. For this power the suitable reduction ratio is obtained by closing the clutch *k'*, opening the clutches *k* and *w* and maintaining the clutch *h* in the same position as in the two previous powers. The cruising turbine is disconnected at this power by opening the clutch *p*.

At full power the clutches *k'*, *k*, *w* and *p* are all open and the low power gear wheel *e* is disconnected from the propeller shaft *c* and the full power gear wheel *d* is connected to the propeller shaft *c* by operating the clutch *h*. This set of clutch connections provides the least reduction ratio. Steam is admitted to the high pressure turbine behind the first stage by the conduit 9 by which means the maximum quantity of steam is passed through the turbines *a* and *b* in series.

The turbines in all the forms described may be of the reaction or of the impulse type, or combinations of these types.

In some cases initial stages of the partial impingement type may be provided such, for example, as are described in United States Patents 958,430, 972,907, 972,908, 986,942, 986,749, and British Specifications 2,295/10, 22,969/10, and 9,005 of 1915.

Again, in some cases there may be employed in place of the ordinary cruising stages hereinbefore described co-acting nozzle sections and reaction cruising stages such as are described in British Patent Specification No. 8,980 of 1911.

Astern turbines, either separate or incorporated in the casings of the main turbines may be arranged to operate any of the propeller shafts.

The clutches employed in the installations described may be of the claw, friction, electrical or any suitable type. They may be provided with operating mechanism by means of which the various clutches can be operated simultaneously when changing from one power to another.

It will be seen that in installations according to this invention, while different revolution ratios between the turbines and propeller shaft may be obtained with a small amount of gearing, the same speed relation between the various turbines is maintained under all power conditions.

Having now fully described and ascertained our said invention, and the manner in which it is to be performed, we declare that what we claim is:

1. A turbine installation for ship propulsion comprising in combination a propeller shaft, high and low pressure turbine units adapted to drive said propeller shaft, gearing between one of said turbine units and said propeller shaft at full power, supplementary gearing giving a different rate of revolution in conjunction with said full power gearing at low power, as set forth.

2. A turbine installation for ship propulsion comprising in combination a propeller shaft, high and low pressure turbine units adapted to drive said propeller shaft, reduction gearing between one of said turbine units and said propeller shaft and secondary reduction gearing in series with said gearing at low powers.

3. A turbine installation for ship propulsion comprising in combination a propeller shaft, high and low pressure turbine units, a primary gearing, a secondary gearing, said primary gearing driving said propeller shaft from said units at full power and said secondary gearing driving said propeller shaft from said units at low power, said secondary gearing being directly driven by a member of said primary gearing.

In testimony whereof we have affixed our signatures.

CHARLES ALGERNON PARSONS.
